APPLICATION FILED JULY 31, 1916.

Inventor:

George L. Seearos.
By Herbert G. Fletcher
Atty.

UNITED STATES PATENT OFFICE.

GEORGE L. SEANOR, OF SAPULPA, OKLAHOMA, ASSIGNOR OF ONE-HALF TO ALFRED S. ABBOTT, OF SPRINGFIELD, MISSOURI.

CONVERTIBLE STOCK-CAR.

1,380,845.

Specification of Letters Patent. Patented June 7, 1921.

Application filed July 31, 1916. Serial No. 112,270.

To all whom it may concern:

Be it known that I, GEORGE L. SEANOR, a citizen of the United States of America, residing in the city of Sapulpa, county of Creek, and State of Oklahoma, have invented certain new and useful Improvements in Convertible Stock-Cars, of which the following is a specification.

The primary object of this invention is to provide a railway stock car of such a construction whereby said stock car can be converted into either a closed or open car.

Another object is to provide a car with an improved wall construction in which the boarding of the car, which comprises the siding can be readily spaced so as to provide ventilation and light in the car for the purpose of conveying stock, or closed so as to provide for the shipping of articles that are to be kept in a dry condition.

A further object is to provide the walling of a car with a series of members that are adapted to be slidably mounted relative to each other, said members adapted to be moved into a spaced apart position as well as being adapted to be closed, in which they will abut each other so as to form a practically weather proof car.

Other and further objects will appear in the specification, and be specifically pointed out in the appended claims, reference being had to the accompanying drawings exemplifying the invention, and in which,

Figure 1 is a side elevation of a railway box car, central portions thereof being broken away, showing this improved construction applied thereto, the slidably mounted members on one side of the door being shown spaced apart, whereas the other members are shown in their closed position in which they abut each other.

Fig. 2 is a fragmentary, longitudinal section, showing a portion of the interior of the car.

Fig. 3 is an enlarged vertical section taken on the line III—III of Fig. 1.

Fig. 4 is an enlarged section taken on the line IV—IV of Fig. 1.

Fig. 5 is an enlarged fragmentary, horizontal section taken on the line V—V of Fig. 1.

Fig. 6 is a section taken on the line VI—VI of Fig. 1.

Referring to the drawings, 1 designates the bottom sills of the car which support the flooring 2 and side walls 3, said walls having the roof 4 mounted thereon. Mounted on said sills 1 are end posts 5 and side posts 6 and mounted between the two intermediate side posts 6 is a slide door 7.

This invention relates more particularly to the car walls, in which there are a series of slidably mounted members 8, said members being mounted between the posts 6 and the vertically arranged guiding bars 9, said bars being mounted inside of the car. The ends of the members 8 are mounted in vertically formed end pockets 10. In the construction shown in the drawings, a longitudinally arranged pocket 11 is mounted above the uppermost member 8. Pivotal connecting the slidably mounted members 8 by pivotal connections 12 are a plurality of operating link bars 13, the lower end of each of said bars being pivoted at 14 to a stationary mounted board 15. The uppermost slidably mounted member has a reduced portion 16 formed thereon, said reduced portion being adapted to reciprocate in the pocket 11. Connecting said uppermost member 8 at 17 is one end of a connecting rod 18, said connecting rod being pivotally secured at 19 to a segmental gear 20, the teeth of said gear being in mesh with a worm gear 21 which is secured to the vertically arranged shaft 22, said shaft being turnably mounted in the bearings 23.

Mounted in the guideways formed by the posts 6 and guiding bars 9, above the horizontally arranged pocket 11, are a series of 90 slidably mounted members 24, said members having their ends mounted in the end pockets 10. Securely mounted in the upper portion of the pockets 11 by lag screws 25 is a stationary member 26, and pivoted at one 95 of their ends to said member 26, as shown at 27, are a plurality of operating bars 28, each of said bars being pivoted as shown at 29 to the slidably mounted members 24.

Pivoted to the uppermost member 24 is 100 one end of a connecting rod 30, said rod having its opposite end connected to a segmental gear 31, the teeth of which are in mesh with a worm gear 32, said gear being secured to the vertical shaft 22. The uppermost member 24 is adapted to reciprocate behind a

solid upper structure 33 which is built downwardly a distance from the roof 4 of the car.

The construction just given, relative to 5 the members 8 and 24 and their operating segments 20 and 31 respectively, is identical with the slidably mounted members 34 and 35 which comprise the convertible wall of the car on the opposite side of the door 7 in 10 which there are operating rods 36, pivotally connected to the members 34, and connected to the uppermost member 34 is a connecting rod 37 which is also connected to a segmental gear 38, said gear being in mesh with 15 the worm gear 39, which is mounted on the vertical shaft 40.

The uppermost member 34 is adapted to reciprocate in the horizontally arranged pocket 41, the ends of said members being 20 adapted to reciprocate in the vertically formed end pockets 42. The members 35 are operatively connected together by the operating rods 43, and connected to the uppermost member 35 is one end of a connecting rod 44, said rod being connected at its opposite end to the segmental gear 45 which is in mesh with the worm gear 46, said gear 46 being mounted on the vertical shaft 40.

The slidably mounted members 8, 24, 34 30 and 35 preferably have tongues 47 formed on their upper edges, whereas there are grooves 48 formed on their lower edges.

In the operation of this improved convertible car, when it becomes necessary to move 35 the slidably mounted members relative to making the car open or closed, when the operating handles 49, one of which is mounted on the lower end of each of the vertically arranged shafts 22 and 40, are manipulated, 40 motion will be transmitted by the worm gears carried by said shafts to the segmental gears and the connecting rods which are connected to said segmental gears, will manipulate the operating link 45 rods which are connected to the slidably mounted members thereof, rocking them on their fulcrum bolts 14 and spacing said members or drawing them together so that they will abut each other, thereby 50 either converting the car into a stock car for the shipping of cattle or converting the car into a closed one for the shipping of articles that might be damaged by the elements.

If desired, the end walls of the car can 55 be provided with a series of slidably mounted members as just described relative to the side walls of the car. The method of operating the slidably mounted members by means of the segmental gear and worm and 60 operating rods in connection therewith as shown can be changed to any other desired form of mechanism that will properly cause the slidably mounted members to travel in their guideways relative to open or closed 65 positions.

The vertically arranged pockets such as 10 and the horizontally arranged pocket such as 11 merely serve as a nesting place for the displacement of portions of the slidably mounted members that reciprocate 70 therein.

What I claim is:

1. In a vehicle construction, a side wall comprising a series of slidably mounted members, said members adapted to abut each other, means for spacing said members apart and a pocket for receiving the displacement of one of said members, said pocket and said member to be displaced therein providing means whereby when said 80 members abut one another a continuous wall is formed.

2. A convertible box car comprising closure walls having a series of horizontally mounted members arranged in gangs, each 85 gang forming a wall section, operating rods pivotally connecting the members of each gang, and means for operating said rods for sliding said members in the same plane toward each other or apart while maintaining their horizontal positions, said members of each gang when abutting each other providing a closed wall section.

3. In vehicle construction, a side wall comprising a series of horizontally arranged 95 members arranged one above another and adapted to abut each other, means for providing a lateral and a vertical movement to said members comprising angularly arranged rods pivoted to said members, vertically formed end pockets for the reception of the ends of said members, and a horizontally arranged pocket for the reception of the uppermost one of said members.

4. A convertible box car comprising a series of horizontally disposed members arranged one above another, a vertical axially rotatable shaft operatively connected to said members for moving and separating them in the same vertical plane only when they 105 are impelled by said shaft and maintaining them in spaced relation to form a ventilated stock car, and for drawing them together in the same manner for causing said members to abut along their longitudinal edges 110 to form a closed box car adapted to carry grain or other produce.

5. A convertible box car, comprising a series of horizontally disposed members arranged one above another, link bars pivotally connecting said members, operative means connected with said members for causing a lateral rocking movement of said link bars in the same plane to cause a rocking movement about fixed fulcrum points to separate them and to maintain them in spaced relation to thereby form a ventilated stock car, and to move them into abutting relation to form a closed box car.

GEORGE L. SEANOR.
